UNITED STATES PATENT OFFICE.

MICHAEL J. BROSNAHAN, OF ST. LOUIS, MISSOURI.

TAILOR'S APPLIANCE.

No. 850,340.

Specification of Letters Patent.

Patented April 16, 1907.

Application filed June 18, 1906. Serial No. 322,215.

To all whom it may concern:

Be it known that I, MICHAEL J. BROSNAHAN, a citizen of the United States, residing at St. Louis, State of Missouri, have invented 5 certain new and useful Improvements in Tailors' Appliances, of which the following is a full, clear, and exact description, reference being had to the accompanying drawings, forming a part hereof.

10 My invention has relation to improvements in tailors' appliances; and it consists in the novel construction of device more fully set forth in the specification and pointed out in the claim.

15 In the drawings, Figure 1 is a perspective view showing the application of my device when measuring for a coat. Fig. 2 is an enlarged plan view thereof. Fig. 3 is an edge view of the appliance, showing by dotted 20 lines the position of the spring when bent or bowed to grip the garment of the wearer; and Fig. 4 is a section on line 4-4 of Fig. 2.

The object of my invention is to provide a 25 device to which the end of a tape-measure may be secured, such device having means whereby the same can be fastened to the garment during the measuring operation. The device or appliance being thus held in a permanent position on the body of the person 30 whose measure is being taken insures absolutely-accurate results, since the measurements are made from a fixed point or a point which does not shift its position during the handling of the tape. The necessity for a 35 fixed point of measurement is of special importance in taking measurements across the shoulders, down the back, along the sleeves, and the like, where utmost accuracy is required for purposes of drafting a pattern.

40 In detail the invention may be described as follows:

Referring to the drawings, 1 2 represent the long and short legs or members of an angle-piece or square, the leg 1 having an extension 1' projecting beyond the leg 2. In line with or opposite to the leg 2 is a flexible 45 yielding spring member or tongue 3, terminating in a point or tooth 4. In applying the device the same is placed under the arm,

the arm is allowed to drop, Fig. 1, and the 50 spring 3 is then bent or bowed slightly outward to cause the tooth 4 to embed itself in the goods of the garment or coat C, Fig. 3. The tooth thus embedded in the goods prevents the appliance from shifting its position, 55 permitting the cutter to take accurate measurements from a fixed point on the appliance. This point corresponds to the center of rotation of the rotatable swivel 5, the latter being pivoted to swing in the plane of the 60 legs 1 2. An offset or shoulder 6 is formed in the swivel, said shoulder corresponding in position to the end of the tape 7, secured to the swivel, the shoulder being further positioned so as to swing into alinement with 65 either of the contiguous inner edges of the legs 1 2, Fig. 2, so that when the swivel is swung parallel to the leg 1 the end of the tape will be in line with the inner edge of the leg 2, and when swung parallel to the leg 2 70 the end of the tape will be in line with the contiguous edge of the leg 1, and since the pivot about which the swivel (and hence the tape) swings is fixed by reason of the firm attachment of the appliance to the garment it follows that the tape may be swung in any direction from a fixed point, and hence most accurate results are assured. 75

Having described my invention, what I claim is—

80 A tailor's appliance comprising an angle-piece composed of two legs, a yielding member opposite one of the legs having a terminal tooth for embedding itself in the garment, of the wearer, over which the measurement is 85 being taken, a swivel pivoted to rotate in the plane of the legs and having an offset positioned to aline with the inner edge of one of the legs when swung to a position parallel with the contiguous leg, and a tape-measure 90 secured to the swivel and terminating at the offset, substantially as set forth.

In testimony whereof I affix my signature in presence of two witnesses.

MICHAEL J. BROSNAHAN.
